UNITED STATES PATENT OFFICE.

MARK THOMAS DENNE, OF HIGHGATE, LONDON, ENGLAND.

PULLING-OVER MACHINE.

Application filed February 21, 1921. Serial No. 446,773.

(GRANTED UNDER THE PROVISIONS OF THE ACT OF MARCH 3, 1921, 41 STAT. L. 1313.)

To all whom it may concern:

Be it known that I, MARK THOMAS DENNE, a subject of the King of Great Britain, residing at Highgate, London, N. 6, 5 England, have invented new and useful Improvements in Pulling-Over Machines, of which the following is a specification.

This invention has reference to improvements in pulling-over machines which are 10 employed in the manufacture of boots and shoes.

So far as affects the scope of my invention, it may be said that there are two types 15 of power pulling-over machines, one in which the stretching of the upper is effected manually, and the other in which the stretching is effected by power.

The first of these is employed for high-class work because, as is well known, practically no two uppers, even though to outward appearance exactly similar, require the same degree of tension to take the stretch out of them, so that every upper requires or should receive individual attention, by an 25 experienced operator, if best results are to be obtained.

In the other type the stretching is effected by power, the force of which must be determined before starting the machine, and in 30 which the operator, having adjusted the upper, starts the machine which effects the stretching.

In both the aforesaid types of machines the laying of the upper under the last (i. e. 35 on to the insole on the bottom of the last), the operation of the tack supply mechanism, the tacking and the eventual return of the operating parts to their normal position, are effected by power.

40 When the operator has to do the stretching—and assuming he has to deal with a considerable amount of work—the physical strain—even when comparatively light uppers are being dealt with—is such that, after a time, the speed of output becomes less and less, and often the quality of the work also suffers. When the stretching is done by power, every upper of any particular series is subjected to the same strain (according to 45 the adjustment made prior to starting the machine) and consequently some uppers will be understretched, whilst others, at times, are stretched or strained too much, so that, although the speed of output is higher and 50 may be maintained practically constant for

a quite long period of time, this method is only suitable for the cheaper grades of goods.

55 My invention is intended to obviate the defects of both types of machines whilst retaining their respective advantage to a high degree, that is to say, when using a pulling-over machine provided with my invention the operator is enabled to do best quality work at practically the same speed as is possible with the use of machines in which the stretching (as well as the other operations incidental to the complete pulling-over operation) is effected by power, and further, 60 he will practically not be subjected to any greater physical strain than when using said latter type of machine.

To this end an important feature of my invention consists in a power pulling-over machine in which the stretching of the upper as well as the subsequent operations of nailing etc. are effected by power, but with this essential proviso that so far as the stretching of the upper is concerned the power actually applied is determined by and is at all times under the complete control of the operator during the whole time that the stretching is being effected or proceeding, so that he may subject one upper to a greater or to a less strain than the upper immediately before dealt with, and he may cause the stretching force to be applied gradually or otherwise, and he may "humor" the upper; in fact he can deal with the upper precisely in the same way in which he is accustomed to do when using machines in which he manually effects the stretching, with the difference that, when using a machine constructed according to my invention, he is not subject to the physical strain involved in stretching the upper but need merely operate an ordinary treadle lever (or equivalent) having the usual adjustable spring resistance.

100 A preferred constructional form of my invention comprises the addition to a pulling-over machine having the usual driven shaft and cam cylinder, of an auxiliary power driven shaft—which, preferably is in constant rotation whilst the machine is in use—and to which the operator can couple or connect mechanism by the operation of which relative movement is imparted to the last and the pincers to stretch the upper, the 105 coupling or connecting means and the means 110

- to actuate these being of such a character that the operator has them under such complete control that he may cause from time to time any desired degree or force of tension 5 to be put on the upper, and all this without exerting himself more than is necessary to operate an ordinary treadle lever when no stretching of the upper by such operation is being effected.
- 10 As it is of advantage that the operator may be able to effect adjustments before he has put the final tension on the upper, my invention also contemplates the provision of means, in combination with the aforesaid 15 auxiliary power driven means under the control of the operator, whereby the parts will be automatically locked in any position after tension has been put on the upper; after which the operator may either increase the 20 tension or may relax it, the locking means being adapted to be thrown out of action by the operator so that he may subject the upper to repeated stretching—humoring it is called—whereby to take the stretch out 25 of the leather in successive steps or stages.
- As in some classes of work, e. g. boots and shoes having uppers of a material such as plush, canvas or the like, which, as compared with leather, does not stretch, successive 30 uppers (of a series) must be subjected to practically exactly the same degree or force of tension, my invention further contemplates the provision of means whereby the operator (having determined upon the 35 proper degree of tension) can predetermine a, for the time being, maximum tension to which the upper can be subjected by the aforesaid auxiliary power driven means, so that it will not be necessary for the operator 40 when lasting such boots and shoes, to exercise his judgment, he merely subjecting the successive uppers to the said predetermined maximum tension.
- It happens at times, after the upper has 45 been gripped and to some extent stretched that the operator desires to relax temporarily the grip of the pincers to some extent. For example if the operator finds that he has inserted too much of the edge portion of the 50 upper in the pincers he desires to be able to release some of this, and my invention also provides means whereby this may be accomplished.
- To this end my invention consists in the 55 combination with the aforesaid auxiliary power driven mechanism means whereby the operator from time to time may cause any desired tension to be put on the upper, of a pincer control mechanism whereby the 60 operator may bring about any desired temporary relaxation of the firm grip of the pincers on the upper so as to allow the upper to slip or move out of the pincers to the desired extent and whereby he may then 65 instantly re-establish the firm grip, the said

means being of such a construction that the operator may bring about a complete releasing of the upper should this be necessary, the parts then returning to their initial or starting position to enable the operator to 70 start de novo.

It also happens at times after slight tension has been put on the upper, that the operator finds it desirable to move the pincers nearer to or away from the last and 75 to lock them in the adjusted position, and my invention therefore also comprises means whereby this can be effected and which may be operated whilst the tension on the upper is maintained.

My invention is illustrated in the accompanying drawings in which Fig. 1 is a side elevation of a complete pulling-over machine in which mechanisms are included which do not form a part of the present application 85 and are not therefore described in detail.

Fig. 2 illustrates in side elevation the upper portion of one pair of pincers, of which, as is usual, there will be three in the machine viz. one at the toe and one on each side of 90 the fore-part; the pincers being in closed position.

Fig. 2^a illustrates a side elevation, the lower portion of one pair of pincers; the position of the parts being that assumed 95 when the pincers are in open position.

Fig. 3 illustrates a constructional form of means whereby the operator can cause relative movement to be imparted to pincers and the last support.

Fig. 4 is a plan view of a part of Fig. 3,

Fig. 5 shows in side elevation the means whereby the pincers may be adjusted to suit different sizes of lasts.

Figs. 6 and 7 are a plan and edge view 105 respectively of a part of the means illustrated in Fig. 5.

Fig. 8 is a plan view of the spring cushioning device whereby the pincers will be operated by a yielding pressure to lay the 110 edge of the upper under the last, and

Fig. 9 is a half section on line A, B, Fig. 8 viewed from left to right.

Owing to the fact that in Fig. 1 it is not possible to illustrate the various mechanisms 115 fully, I propose to refer mainly to the detail drawings in the first instance as by this means a complete understanding of my invention may be had, reference to Fig. 1 being from time to time made so that the 120 relative location of the interdependent parts may be seen.

In Figs. 1 and 2 the numeral 1 indicates a bar—which I will refer to as the main pincers bar—which at its lower end has connected to it a link 3 which is pivoted at 4 to the frame of the machine. The position of these parts can be seen in Fig. 1 in which the frame of the machine is marked 142. 2 is a trunnion pin which is carried in a slide 130

150 (Figs. 1 and 8) and which slide supports the weight of the bar and its mechanism. The upper end of the main pincers bar has attached to it a block 7 that carries the fixed 5 jaw 5 this latter being secured in position by the set screw 6. On an extension from the block 7 is a pivot 8 that carries the movable jaw 9, a spring 10 acting to maintain the jaw 9 against the fixed jaw 5. The 10 shank of the jaw 9 extends downwardly at 11 and has a tail piece 12 which, as will be described serves as an inclined plane. At 13, the main pincers bar carries a rocking-bar 14 one end of which is provided with an 15 antifriction roll 15 and the other end of which is bifurcated to engage a pin 16 on the upper end of a vertical rod 17, the arrangement being such that if the rod 17 is raised—as it is shown at its upper end and 20 which is normally effected by a spring 18—the cam roll 15 will travel along the inclined plane 12 and close the jaw 9, whereas on the reverse movement of the rod 17 the jaw 9 will be released, allowing the spring 10 25 to open it.

The jaws are normally open, and means are provided whereby the operator on depressing a treadle to a very limited extent, the spring 18 will be set free to close the 30 jaws on to the previously inserted edge of the upper. Should it then be necessary to adjust the upper the operator can cause the pincers to relax their grip to a sufficient extent by his merely depressing the treadle to 35 a further (still not to its full) extent. Should it however be necessary to open the jaws completely, the operator can effect this by depressing the treadle to the full extent, when the parts will have been returned to 40 their normal positions and having released the treadle, the operator can start de novo. I now propose to describe the means whereby these movements of the pincers jaws can be brought about but must first 45 point out that whilst the jaws are shown closed, the mechanism now to be described is in the position they occupy when the jaws are open, the rod 17 being for this purpose shown broken.

50 On the bottom end of the rod 17 is a block 19 secured in position by a set screw 20. The said block has two lugs 21 and 22. The lug 21 is adapted to be engaged by a hook 24 which is pivotally mounted at 23 on the 55 pincers bar 1 a spring 25 acting on a tail extending down from the shank of the hook 24 acting to maintain normally the said engagement. When the parts are so engaged the rod 17 will be in its lowermost 60 position and consequently the pincers will be open.

The main pincers bar is formed with a bearing on which a vertical rod 26 is adapted to slide, the said rod having connected 65 to it one end of a spring 27 the other

end of which is connected to the main pincers bar and which spring tends to maintain the rod 26 in its raised position. The lower end of the rod 26 is connected by a chain 28 to one end of a lever 71 (Fig. 1) the other 70 end of which is carried by a shaft 72, and which lever is connected by a link 73 to the appropriate treadle 75. 74 (Fig. 1) shows a similar link whereby the side pincers operating levers—similar to 71 are connected 75 to their appropriate treadle 76.

The rod 26 is provided with a lug 29 that projects so as to be engaged against the lug 22 on the block 19 when relative movement is imparted in one direction to the parts 26 80 and 19, and also with a spring pawl 30 the spring 31 of which acts normally to maintain the pawl projecting beyond the side face of the rod 26 and which pawl, when the machine is in its normal or starting position, engages against a hump 32 on an extension of the shank of the catch 24.

The block 19 has connected to it a link 33 the lower end of which (see Fig. 1) is connected to one end of a rocking lever 79, 90 mounted on a pivot 80, the opposite end of which is engaged by a plate 81 on a stem that is moved by the rocking of a bell-crank lever 83, 84 mounted at 85 and having a cam-roll that engages a suitably formed cam groove (not shown) in a cam cylinder 87. The cam cylinder is carried on a cam shaft 88 which receives rotary movement from the usual belt pulley 300 through the intermediary of any suitable gearing 301. 100

At one end the cam shaft 88 is provided with a crank disk 89 the crank pin 90 on which engages a block on the end of a rod 91 through which in the well known manner the nail supplying apparatus 92 is operated to supply tacks down the usual raceways 93 and after the tacks are reversed they pass head first down flexible tubes 94 to the nosepiece 63 (Fig. 2) of the pincers, from which they pass through the orifice 62 to the nail driving aperture 47.

When the hook 24 engages the lug 21 on the block 19, the rod 17 will be drawn down—against the action of the spring 18—to its lowermost position and consequently the rocking lever 14 will be in the position in which the roller 15 is raised and consequently the spring 10 will be free to act and open the jaw 9. This is the position of the parts when the machine is in its normal or starting position. As is well understood there are three pairs of pincers in pulling-over machines. As they are similar in construction it will suffice to describe the toe pincers illustrated in Figs. 1 and 2.

When the operator has placed the edge of the upper in the pincers jaw—the last being supported sole down on a rest to be described—he first depresses the appropriate treadle 76 to a slight extent. This action 130

through the mechanism comprising the link 73 lever 71 and chain 28 will pull down the rod 26 to a slight extent, whereupon the pawl 30, by depressing the hump 32 will cause the hook 24 to be disengaged from the lug 21, releasing thereby the rod 17, when the spring 18 will instantly act to swing the rocking lever 14 to the position shown in Fig. 2 and thereby firmly close the jaws 10 to grip the upper. The operator will then depress the appropriate treadle 77 which, through similar mechanism to that just described, will bring about the closing of both the side pincers to grip the upper on each side of the forepart.

Thereafter the operator brings about the relative movement of the last support and the pincers in the direction to stretch the upper.

20 This, in accordance with my invention is effected by power under the control of the operator and in Figs. 1, 3 and 4 a constructional form of my invention is shown in which the last support is moved relatively to the pincers.

25 In Fig. 3 the numeral 190 is intended to indicate the complete pincers just described in detail with reference to Fig. 2. The last support comprises a bar 101 which is slideable in a guide 113 and has a pivot 102 on which the toe rest 103 is mounted, a spring 104 serving to maintain said rest in its raised position. 105 is the forepart rest that is adjustably fixed by a setscrew 106 to a standard 107 that is in turn mounted on a spindle 108 in a bearing of a carriage 110 that is slideable on the bar 101. The standard 107 can be set up or down by turning a handle 111 which rotates the spindle 108 and causes a toothed pinion thereon to ride up or down on a rack on the bar 101, suitable means—for example a set screw 112—being provided to lock the parts in their adjusted position.

40 45 The lower end of the bar 101 is connected by a link 114 to a cross-pin 115 on one end of a rocking frame 116 which rocks on trunnion pins 117.

50 Supported in bearings at a suitable part of the machine is a shaft 136 which has a belt pulley 137 that is constantly driven, and which shaft carries the parts 117 and 116 referred to, as well as friction discs 132, 133, the latter of which is slideable and is controlled by a treadle lever 138 pivotally mounted on a shaft 140 and normally held raised at its front end by a spring 139. The friction discs are normally held apart in the usual manner by a spring (not shown) 55 and the lever 138 has an extension which carries on opposite sides of the bearing supporting the shaft 136, pins such as 141 which engage slide pieces 142, the arrangement being such that if the treadle rod 138 be depressed the friction discs will be en-

gaged. The friction disc 132 is provided with a bevel wheel 134 with which an arc shaped rack 135 gears, the said rack being carried by the rocking frame 116 (see Figs. 3 and 4) so that when the friction discs are made to engage; the disc 132 will rotate the gear 134 and this will cause the frame 116 to be rocked thereby raising the rod 114, bar 101 and the last supports 103 and 105 and, as at this time the edge of the upper will have been gripped in the pincers, the upper will be subjected to tension, the amount or degree of which will be dependent upon the force with which the friction discs are made to engage with each other. The operator can then put any degree of tension on the upper.

As already premised when plush, canvas or similar comparatively non-stretchable uppers are used, all of which (of a series of uppers) will require to be subjected to practically exactly the same degree of tension I provide means whereby I may limit the amount of tension which can be put on or in other words I provide means whereby the operator may predetermine a, for the time being, maximum tension (this being the tension suited to the upper material in use) which can be applied. Merely by way of example I may apply means whereby the downward movement of which the treadle 138 is capable may be limited more or less as may be necessary and I have illustrated purely diagrammatically a simple means whereby this may be effected. The said means comprise a hook 250 (Fig. 3) that is adapted to engage the under edge of the treadle bar 138 and which may be set up or down by a nut 251 which rests on a fixed flange 252 of a suitably supported bracket 254 and which is engaged with the screw-threaded end 253 of the hook 250. Thus by turning the nut in one or other direction the distance or depth to which the treadle rod can be depressed may be limited to any desired extent and thereby the maximum degree of frictional engagement of the friction disc will likewise be limited. Having made the aforementioned adjustments of the nut 251, so that the proper tension is applied to the first upper of a number, the operator need only depress the treadle to the, for the time being, full extent when lasting successive plush, canvas or like uppers, and they will all be subjected to the proper tension without the operator having to exercise his judgment.

110 Means will be provided (which will be described later on, when the tensioning of a leather upper is being dealt with) whereby the last support is locked when the desired full tension has been applied to the upper.

115 After this the operator will, in the usual manner, start the machine whereby the laying of the edge of the upper under the edge

of the last, the subsequent tacking, the final releasing of the work, and the return of all the parts to their normal positions will all be automatically effected, but as the means whereby these automatic operations are effected form no part of the present application, they are not further described.

It is well known that, in order to obtain best work when leather uppers are being used, each upper should receive individual attention, and in that case the hook 250 will be thrown out of action so that the operator will be free to apply any desired degree of tension up to the maximum that can, within the compass of the friction clutch, be applied.

Mounted to be slidable in the bracket 118, carried by the frame of the machine and which bracket supports the guide or slide 20 113 hereinbefore referred to, is a pawl 120 that is adapted to be engaged with a toothed rack 119 on the bar 101 (Fig. 3). The pawl will be pressed on by a spring (not shown) that tends to bring about such engagement. 25 Pivots mounted on the bracket 118 is a finger 121 that engages with an aperture or slot in the shank of the pawl 120 and a handle 123 secured to the boss of the finger is provided whereby the finger can be moved 30 to the position shown to permit the pawl to engage the rack or the finger may be moved or swung to withdraw the pawl from engagement with the rack 119 and thus free the bar 101. In practice it is usual in such pawl 35 and rack devices to provide two or even more pawls located at slightly different altitudes with respect to the rack so that a very fine adjustment may be had without requiring the pawl to be provided with equally 40 fine teeth and I have adopted this in my arrangement. A spring catch 122 is provided that engages in one or other of two notches in the boss of the finger 121 so as to retain this in either position to which it may 45 have been adjusted.

With the arrangement thus far described, the operator having gripped the upper in the pincers, he may in the first instance withdraw the pawl 120 from the rack 119. 50 Thereafter he may move the treadle down in successive stages—preferably releasing it after each depression—so as to take the stretch gradually out of the leather. This is known as humoring the upper. After 55 this preliminary stretching (or without doing so if the operator thinks this to be unnecessary in any particular case) the operator will release the pawl 120 and then put tension on the upper to the desired extent sufficient to enable him to see whether the upper is in every way properly positioned. He may now release the treadle, when the pawl 120, by its engagement with the rack 119, will maintain the tension on the upper 60 by reason of its having locked the bar 101

against downward movement. The operator is then free to move about to effect any desired adjustments of the upper (and of the pincers to and fro in the well known manner). Having seen that all is in order, he 70 may depress the treadle so as either gradually i. e. step by step or at once to put the final tension on the upper when the pawl will, as before, maintain the parts locked, enabling the operator to take his 75 foot from the treadle lever 38.

As already mentioned, the operator then starts the machine when the other operations incidental to the completion of the work will be effected automatically as is 80 well known.

So far as the automatic disengagement of the pawl 120 with the rack 119 is concerned (which must be effected after the work is completed) I provide a sliding plate 85 126 the upper end of which is tapered and adapted, when pushed against the tapering end of the pawl 120, to push this back. The said sliding plate has a slot in which one arm 125 of a bell crank lever that is mounted 90 on a pivot 124 engages, the other arm 127 of which has connected to it a rod 128 the other end of which is connected to a lever 144 which in any usual manner is pivotally supported and at its other end 95 carries a cam roll that is engaged in a cam groove in the main cam disc 87.

The trunnion 2 of the pincers bar 1 is carried by a slide 150, Figs. 1, 8 and 9, that is adapted to slide in suitable guide-ways, 100 such as 150^a. Below the slide 150 is another slide 151^a having racks 151 on either side which are in gear with toothed pinions 152. A stem 170 and a stud or abutment 171 is carried by the upper slide 150, said slide 105 having the web W which supports the stem 170. The stem 170 has mounted on it a rotatable sleeve 172 having a depending lug 174 that is normally maintained in contact with the stud 171 by the action of a spring 173 one end of which is hooked on a stud 175 on the slide 151^a and the other on a stud 176 carried by the sleeve 172 which spring tends to rotate the sleeve in the direction 110 to maintain contact between the stud 171 and abutment 174. By this arrangement when the toothed pinion 152 is rocked (by means to be described) in the direction to move the pincers under the last, the movement of the bar 151^a will be transmitted 115 through the spring 173 and will then be a yielding movement. The tension of the spring can be adjusted by any suitable means and thereafter the parts locked by a stop pin 177 that can engage against flat faces 120 178 (Fig. 8) on the stem 170, or otherwise.

Movement is imparted to the toothed pinions 152 (which are carried on spindles such as 166 (Fig. 1) by a plate or slide 153 125 which has racks such as 165 that engage 130

with the pinion 152. The slide 153 (Figs. 1, 5, 6 and 7) derives reciprocating movement from a suitable cam (not shown) in the main cam cylinder 87. The said slide 5 153 is not, however directly connected with the cam there being means intermediate said parts whereby the length of the slide 153 may be adjusted so that by this means the position of the pincers may also be adjusted to adapt them for lasts of different sizes. For this purpose the slide 153 has a slot or slideway to receive a bar 154 (Figs. 5, 6 and 7) that carries the supporting 10 spindle 155 of a cam roll 156 (Figs. 1 and 15 5) that engages in a cam race (as already stated, not shown) in the cam cylinder 87). The bar 154 is adjustably connected to the slide 153 by the following means. The slide 153 is provided with a toothed rack 157 and 20 the bar 154 with a corresponding rack 159. This latter rack is formed on the end of a block that is slidable in a fitting in the bar 154 which block is normally pressed so that its rack engages the rack 157 by springs 25 158. When it is required to alter the position of the pincers—for larger or smaller lasts—the rack 159 is disengaged from the rack 157 (by means to be described) and then the handle 167 (Fig. 1) which is fixed 30 to the spindle 166 of the toothed pinion 152, is moved to rotate the said pinion in the appropriate direction and to the proper extent, which will move the rack bar 151 (and with it the slide 150 and the pincers) and 35 also the slide 153. After this, the rack 159 is again engaged with the rack 157. To effect this disengagement of the racks, I provide (see Fig. 5) a cam 162 on a spindle 161 which is suitably supported on a fixed 40 part of the machine and which cam may be rotated by moving a hand lever 163 secured to the spindle 161. The cam when so moved, acts against a spindle 164 that has a notch 45 cut in it in which a lug 160 on the block 159 is engaged and by this the block is pressed back—against the action of the springs 158 and the rack 159 is disengaged from the rack 157. After the required 50 adjustments have been effected, the handle 163 is moved back to its normal position when the springs 158 will cause the said racks to be again engaged. As already stated, the 55 said adjustment of the pincers can be effected whilst tension is maintained on the upper.

In Fig. 2 of the drawings means are illustrated whereby the upper is held tightly against the last to permit the pincers to release the upper in order to move a further distance after which the tacks are driven and also means that control the tack driver, but as these form no part of this present application they need not be further described.

I wish it to be understood that although 65 I have described and illustrated my inven-

tion as applied to a pulling-over machine in which the work is held sole down, I do not limit the scope of my invention thereto and that whenever I refer in the claims to the upper being laid under the last I wish it to be understood that this expression is intended to describe merely the movement of the pincers whereby in the case of welted boots and shoes the edge of the upper is brought up against the lip of the insole or in the case of machine sewn boots and shoes it is brought further over the edge of the insole and nearer to the centre of the sole of the last altogether regardless of the actual position in which the last is supported.

What I claim is:—

1. A pulling over machine having in combination, a last support, a plurality of pincers, automatic power-actuated means for actuating said pincers to lay the marginal portion of the upper over the edge of the sole of the last, and other power-actuated means operable throughout the operation and entirely under the control of the operator to bring about a relative movement of the last support and all the pincers simultaneously, to stretch the upper about the last.

2. A pulling over machine having in combination, pincers, automatic power actuated means for actuating said pincers to lay the upper over the edge of the sole of the last, an auxiliary independent power driven shaft, means for imparting relative movement to the last and the pincers, means for controlling said last mentioned means in applying tension to the upper, and means operable throughout the operation and entirely under the control of the operator to operate the controlling means through said independent power-driven shaft.

3. A pulling over machine having in combination, pincers, automatically power actuated means for actuating the pincers to lay the upper over the edge of the sole of the last, an auxiliary power driven shaft, means under the control of the operator to cause said auxiliary power driven shaft to impart a desired relative movement to the last and pincers to stretch the upper to the desired extent, and means for limiting the amount of tension to which the upper can be subjected by the auxiliary power driven shaft.

4. A pulling over machine having in combination, pincers, automatically power actuated means for actuating said pincers to lay the upper over the edge of the sole of the last, an auxiliary power driven shaft, means to limit the degree of tension put upon the upper through said auxiliary power driven shaft, and means to utilize said auxiliary power driven shaft to gradually increase or decrease the tension on the upper without intermediate relaxation of the tension.

5. A pulling over machine having in com-

bination, pincers, automatically actuated means for actuating said pincers to lay the upper over the edge of the sole of the last, an auxiliary power driven shaft, means under the control of the operator to apply the desired extent of movement to the last support relative to the pincers, a treadle, connections between the treadle and said last through said auxiliary shaft, whereby a partial operation of the treadle will cause a closing of the pincers and further movement of the treadle will cause a desired relaxation of the grip of the pincers without affecting the tension means prior to the complete release of the upper.

6. A pulling over machine having in combination power actuated pincers which are normally open and which are stationary while a movable last support brings about the tensioning of the upper, a treadle, means controlling the pincers and actuated by the treadle whereby a partial depression of the treadle effects the firm closure of the pincers on the previously inserted upper, a further partial depression of the treadle brings about a partial relaxation of the firm grip of the pincers and a complete depression of the treadle brings about a complete release of the upper, and means whereby before the complete release is brought about the operator can subject the upper to tension by coupling the work support to an auxiliary power driven shaft.

7. A pulling over machine having in combination, a last support, a plurality of pincers, automatically power actuated means for moving said pincers to lay the margin of the upper over the edge of the sole of the last, a separate power actuated shaft, a friction clutch to be driven by said latter shaft, and means entirely controlled by the operator whereby the friction clutch is made to impart relative movement to the last support and all the pincers simultaneously in the direction to stretch the upper over the last.

8. A pulling over machine having in combination, a last support, a plurality of pincers, automatically power actuated means for actuating said pincers to lay the margin of the upper over the edge of the sole of the last, a separate power actuated shaft, a friction clutch, means connecting one member of the friction clutch to the last support, and means entirely under the control of the operator for frictionally coupling said member with the separate power driven shaft.

9. A pulling over machine having in combination, a last support, a plurality of pincers, automatically power actuated means for actuating said pincers to lay the margin of the upper over the edge of the sole of the last, a separate power actuated shaft, a friction clutch, means connecting one member of the friction clutch to the last support, a treadle and connections therefrom to couple the said member frictionally with the separate power driven shaft.

10. A pulling over machine having in combination a last support, pincers, a constantly-driven shaft, a friction member rotated by said shaft, a second friction member normally stationary, a treadle, connections therefrom to bring the friction member into engagement to rotate the second member, means controlled by the friction members to bring about relative movement of the last support and the pincers to stretch the upper, and connections between the normally stationary friction member and the last support, whereby on rotation of said member movement of the last support is brought about, said last-named connections comprising a toothed wheel, a rack in engagement therewith, a rocking frame to carry the rack, and a link connecting said rocking frame with the last support.

11. A pulling over machine having in combination, a last support, pincers, an intermittently driven shaft, a constantly driven shaft, connections between the former shaft and the pincers to bring about movement of the pincers in a plane substantially parallel with the plane of the sole of the last, and means actuated by the latter shaft to bring about relative movement of the last support and the pincers in a plane substantially at right angles with respect to the first mentioned plane.

12. A structure as specified in claim 11, in which the means actuated by the constantly driven shaft comprise in combination, a constantly driven friction member, a normally stationary friction member, and means actuated solely by the operator to bring the friction members into engagement with any desired and variable degree of pressure, for the purpose set forth.

13. A structure as specified in claim 12, in combination, a treadle and connections therefrom and one of the friction members to bring about a movement of approach between the two friction members, for the purpose set forth.

MARK THOMAS DENNE.
